COLLAPSIBLE BOX OR CARTON

George C. Nydegger, Chicago, Ill.

Application February 23, 1937, Serial No. 126,961

8 Claims. (CL 229—29)

My invention relates to improvements in an inexpensive collapsible box or carton and particularly to a box or carton for carrying eggs, fruit or fragile articles.

5 An object of my invention is to provide a simple and easily assembled carton capable of housing a plurality of such articles in such a manner as to prevent breakage.

Another object is the provision of a carton or 10 box from a single blank of material which may be easily assembled from knockdown position by a single operation without the assistance of assembly framework.

15 A further object is the provision of a carton of the class described which while securely cushioning and securing the articles contained therein will permit of their inspection without opening the carton.

20 These and other objects will be apparent from a consideration of the following description of my invention and by reference to the accompanying drawing, in which

Fig. 1 is a top plan view of my invention showing the carton in assembled position.

25 Fig. 2 is a vertical sectional view taken on line 2—2 of Fig. 1.

Fig. 3 is a cross-sectional view taken on line 3—3 of Fig. 2.

30 Fig. 4 is an enlarged fragmentary sectional view of the side clamping means taken on line 4—4 of Fig. 1.

Fig. 5 is a development of the blank from which 35 my carton is constructed.

Fig. 6 is a cross-sectional view similar to Fig. 3 showing the carton in collapsed position.

Fig. 7 is a development of the carton clamping means.

Referring more in detail to the drawing, 1 indicates a blank constructed of fibrous material, such 40 as cardboard, pasteboard or the like, which is appropriately cut and scored to provide the various structural elements comprising my improved carton. The blank 1 includes two imperforate sections 2 and 3 which, as will be hereinafter 45 more fully described comprise the side walls of the finished or assembled carton. The section 2 is defined by score lines or lines of fold 4 and 5 which are positioned in spaced relationship with respect to each other. At the ends of the section 50 2 outwardly extending lugs 6 and 7 are provided, being formed integral with the blank and being defined by score lines or lines of fold 8 and 9, respectively.

The section 3 is similar in construction to the 55 section 2 and is defined by the transverse score

or fold lines 10 and 11 which are positioned in spaced relationship with respect to each other. Outwardly extending lugs 12 and 13 project from the section 3 and are defined by score or fold lines 14 and 15, respectively. As will be herein- 5 after more fully described, the lugs 6 and 12 comprise one end of the assembled carton and the lugs 7 and 13 comprise the opposite end there-

of. Adjacent one side of section 2, and separated 10 therefrom by score line 5, is a perforated section 16 which is provided with a plurality of spaced oval apertures 17. Six of such apertures are illustrated in the drawing, but any desired number may be employed. In addition, said apertures 15 may take any shape or form desired. Adjacent one side of section 3, and separated therefrom by score line 11, is a section 18 similar to section 13, the section 18 being provided with a plurality of appropriately spaced apertures 19 which may correspond in number and shape with aperture 17 20 provided in the section 16.

Section 16 of the blank 1 may be defined on one longitudinal side by score line 5 and is defined on the opposite longitudinal side by score line 20. 25 Likewise, section 18 is defined on one longitudinal side by score line 11 and is defined on the opposite longitudinal side by score line 21. Included between score lines 20 and 21 is a central section 22 which is divided at its longitudinal center by score 30 line 23 providing strip 24 adjacent section 16 and strip 25 adjacent section 18. Section 22 terminates at its ends in locking lugs 26 and 27, respectively, which, as will be hereinafter more 35 fully described, are utilized in locking the carton in assembled position.

A strip 28 is positioned adjacent one longitudinal side of the section 2 and is separated from said section by score line 4. The strip 28 is defined longitudinally by score line 4 and a spaced 40 longitudinal score line 29. Similarly, a strip 30 is disposed adjacent one longitudinal side of section 3 and is separated from said section by the score line 10. The strip 30 is defined along one longitudinal side by the score line 10 and along 45 the opposite longitudinal side by a score line 31.

An end section 32 of the blank 1 is disposed adjacent the strip 28 and is divided from said strip by the score line 29. The section 32 is provided with a plurality of appropriately spaced apertures 33 which correspond in number and position with the apertures 17 and 19. Similarly, the opposite end of the blank 1 comprises a section 34 which is separated from the strip 30 by the score line 31. The section 34 is provided with 55

a plurality of appropriately spaced apertures 35 which correspond in number with apertures 17 and 19. The endmost portion of section 32 comprises a longitudinal strip 36 which is separated from the remaining portion of the section by score line 37. Similarly, the opposite end comprises a strip 38 which is separated from the section 34 proper by score line 39.

In folding the blank 1 to form my improved 10 carton, the blank is folded along the central score line 23 which divides the blank into two substantially symmetrical halves. The blank is then folded along lines 20 and 21, said folding operation being accomplished in the reverse direction 15 to the fold along line 23. In this manner the faces of strips 24 and 25 are disposed adjacent each other, as indicated at 40 in Fig. 3. An elongated area of adhesive 41 is provided upon the mutually contacting faces of the strips 24 and 25 20 and may serve to unite both strips together in the manner illustrated at 40 in Fig. 3. If desired, however, said strips may be disposed in face abutting relationship and maintained in such position by means of stitching, staples or the like 25 (not shown).

The blank may then be folded along lines 5 and 11 in order to provide inclined supporting partitions which will be hereinafter more fully described. The blank may then be folded along 30 the score lines 4 and 10 to form the side walls of the container from the sections 2 and 3. The next folding operation takes place along lines 29 and 31 which provide opposite horizontal shoulders in the finished carton. The blank may then be folded along score lines 37 and 39 to isolate the end strips 36 and 38, respectively. The strips 36 and 38 are provided with areas of adhesive, indicated at 42 in Fig. 5, and in assembling said strips are adhesively secured to the inclined supporting partitions comprising the sections 16 and 18, the operation being so carried out as to bring the endmost portions of the apertures 33 and 35 into respective registration with the apertures 17 and 19. The lugs 6 and 7 and 12 and 13 may 45 then be folded along the respective score lines 8, 9, 14 and 15, and inasmuch as the sections 2 and 3 are positioned oppositely from each other said lugs are folded toward each other. Lugs 6 and 7 carry areas of adhesive 43 whereby said lugs may be adhesively united to the respective lugs 12 and 13. In adhesively uniting said lugs the adhesive areas 43 are joined to the ends 44 of the lugs 12 and 13, said ends being separated from the lugs proper by score lines 45.

55 When the blank is folded and united in the manner above described the lugs 26 and 27, having projecting tongues 46, are positioned over the end walls of the carton comprising the lugs 6, 7, 12 and 13 as indicated generally at 47 in Fig. 4. 60 By so locking the lugs 26 and 27 with the end walls 47 the carton is held in assembled position, as indicated in Figs. 1, 2 and 3. When in this position a plurality of compartments 48 are provided into each of which eggs 49 may be disposed. 65 It can readily be seen that the compartments 48 are formed by the apertures 17 and 19 which serve as a support for the eggs and also by apertures 33 and 35 which embrace the outer sides of the eggs, as illustrated in Fig. 3. In inserting the 70 eggs 49 the partitions comprising the sections 32 and 34 are sprung outwardly in an arcuate direction and exert a slight degree of tension upon the egg, tending to maintain said egg within the apertures 17 and 19 and 33 and 35. Of course, 75 the apertures 17, 19, 33 and 35, when eggs are

to be carried within the container, are slightly smaller in dimension than the dimensions of the smallest egg likely to be encountered so that said eggs will be retained and held by the defining edges of the apertures.

After the carton has been assembled as hereinabove described and a number of eggs have been inserted in the respective compartments 48, a locking element, designated generally as 50, may be utilized to hold the mouth of the carton 10 in desired position. The locking element comprises a paste-board or cardboard blank having a central portion 51 and end portions 52 and 53, the end portions being separated from the central portion by means of score lines 54 and 55. 15

Strips 28 and 29 are provided with cut-out slots 56 and 57, respectively, which are formed along score lines 4 and 10, respectively. In utilizing the locking element 50 the ends 52 and 53 may be inserted in the slots 56 and 57 whereby 20 the central portion 51 serves as a retaining or tying agency. To conveniently manipulate or handle the locking element 50, finger apertures 58 are provided in the central portion 51.

After the locking element has been properly 25 positioned to retain the mouth of the carton in properly spaced position the entire carton may be enveloped in "Cellophane" or wax paper, as indicated at 59 in Figs. 1, 2 and 3. It can readily be seen that inasmuch as the inclined partitions comprising the sections 16 and 18 serve as the bottom of the carton a goodly portion of the egg surfaces are visible from the bottom of the carton. Likewise, inasmuch as the remaining sections are so folded as to provide an open top 35 a large area of each egg will be visible through the "Cellophane" covering from the top. Obviously, this is a decided sales advantage inasmuch as it permits the purchaser to observe the condition and appearance of the eggs carried in the 40 carton. However, by the provision of the apertured sections 16, 18, 32 and 34 said eggs are securely held within the carton and are rendered 45 immovable therein.

When distending the adhesively united carton, 45 that is, distending the same from the position shown in Fig. 6 to the position shown in Fig. 3 the carton may be brought to fully distended position by merely pressing the walls 47 inwardly. In so pressing the walls inwardly the top edges 50 of the walls strike the inclined edges 60 of the lugs 26 and 27 and raise said lugs upwardly to permit the passage of the end walls 47 beneath said lugs. When the end walls come into registration with the slots 61 the resiliency of the 55 central strips 24 and 25 together with that of the inclined partitions comprising sections 16 and 17 cause said lugs to descend substantially automatically to place the lugs in locking relationship with respect to said walls.

In handling the cartons prior to inserting the eggs therein said cartons in adhesively united condition may be collapsed, as indicated in Fig. 6. The collapsing of the carton can be brought about by the disengagement or absence of engagement 65 of the lugs 26 and 27 with the end walls 47. In such collapsed position the carton can be freely folded about score lines 5 and 11, 29 and 31, 4 and 10 and 37 and 39. This permits the various sections to be disposed with their faces in substantially parallel adjacent planes. By the provision of the score lines 45 the lugs 6, 7, 12 and 13 70 may be likewise collapsed and extend outwardly.

It is to be understood, of course, that wherever adhesive areas are used to unite the various ele- 75

ments of the carton, stitching, staples or the like are also contemplated to substitute for the adhesive. Moreover, although my invention has been described with specific reference to an egg 5 container, other articles may be packaged in a device embodying the principles of my invention merely by changing the proportions of the various sections and/or by changing the sizes or shapes of the apertures provided in various of 10 said sections.

I claim as my invention:

1. A carton comprising opposite side walls and opposite end walls, a pair of inclined partitions formed integral with said side walls and disposed 15 within and intermediate the depth of the carton, side supporting partitions formed integral with said side walls and joined to said inclined partitions, said inclined partitions and said side partitions being provided with a plurality of apertures 20 for the reception of a plurality of bulbous solids, and a separate tie-member adapted to connect said side walls together.

2. A carton comprising opposite side walls and opposite end walls, a pair of inclined partitions 25 formed integral with said side walls and disposed within and intermediate the depth of the carton, tongues carried adjacent the ends of said inclined partitions which engage said end walls, side supporting partitions formed integral with said side 30 walls and joined to said inclined partitions, said inclined partitions and said side partitions being provided with a plurality of apertures for the reception of a plurality of bulbous solids, and a separate tie-member adapted to connect said side 35 walls together.

3. A carton comprising opposite side walls and opposite end walls, a partition connected to the lower edge of each of said side walls, said partitions being connected together within the carton, 40 said partitions being inclined toward the intermediate portion of the carton, a side partition connected to the upper edge of each of the side walls, the free ends of said side partitions being joined to an intermediate portion of said inclined 45 partitions, said inclined partitions and said side partitions being provided with registering apertures for supporting bulbous solids of greater maximum dimension than the maximum opening of said 50 apertures, and a transparent envelope of sheet material positioned around said carton.

4. A collapsible carton formed from a unitary blank so scored and folded as to provide opposite side walls, opposite end walls and a plurality of interior partitions, said end walls comprising 55 extensions of said side walls and adapted to be foldably secured together whereby the carton may be collapsed, tongues formed on said interior partitions engageable with said end walls to hold said end walls in unfolded relation and maintain said 60 carton in expanded position.

5. A carton which comprises a pair of side walls and a pair of end walls joined to form a parallelepiped, said end walls being foldable intermediate their length to permit collapsing of the 65 carton, a partition joined to the bottom edge of each of said side walls, said partitions being joined together within the carton so as to dispose said partitions at an angle to said side walls, a side 70 partition joined to the top edge of each of said

side walls, the free edges of the side partitions being joined to an intermediate portion of the respective inclined portions, said side partitions being disposed adjacent the side walls and being bulged outwardly from the line of juncture with 5 the inclined portions, said partitions being provided with a plurality of registering apertures for the reception and support of a plurality of bulbous solids.

6. A carton which comprises a pair of side walls 10 and a pair of end walls joined to form a parallelepiped, said end walls being foldable intermediate their length to permit collapsing of the carton, a partition joined to the bottom edge of each of said side walls, said partitions being joined together within the carton so as to dispose said partitions at an angle to said side walls, a side partition joined to the top edge of each of said side walls, the free edges of the side partitions being joined to an intermediate portion of the respective inclined portions, said side partitions being disposed adjacent the side walls and being bulged outwardly from the line of juncture with 15 the inclined portions, said partitions being provided with a plurality of registering apertures 20 for the reception and support of a plurality of bulbous solids, and a separate tie-member adapted 25 to connect said side walls together.

7. A carton which comprises a pair of side walls 30 and a pair of end walls joined to form a parallelepiped, said end walls being foldable intermediate their length to permit collapsing of the carton, a partition joined to the bottom edge of each of said side walls, said partitions being joined together within the carton so as to dispose said 35 partitions at an angle to said side walls, a side partition joined to the top edge of each of said side walls, the free edges of the side partitions being joined to an intermediate portion of the respective inclined portions, said side partitions 40 being disposed adjacent the side walls and being bulged outwardly from the line of juncture with the inclined portions, said partitions being provided with a plurality of registering apertures for the reception and support of a plurality of bulbous solids, and a transparent envelope of sheet 45 material positioned around said carton.

8. A carton which comprises a pair of side walls and a pair of end walls joined to form a parallelepiped, said end walls being foldable intermediate their length to permit collapsing of the carton, a partition joined to the bottom edge of each of said side walls, said partitions being joined together within the carton so as to dispose said partitions at an angle to said side walls, a side 50 partition joined to the top edge of each of said side walls, the free edges of the side partitions being joined to an intermediate portion of the respective inclined portions, said side partitions being disposed adjacent the side walls and being 55 bulged outwardly from the line of juncture with the inclined portions, said partitions being provided with a plurality of registering apertures for the reception and support of a plurality of bulbous solids, a separate tie-member adapted to connect 60 said side walls together, and a transparent envelope of sheet material positioned around said 65 carton.

GEORGE C. NYDEGGER.
